UNITED STATES PATENT OFFICE.

CHARLES A. BONDZIULIS, OF WATERBURY, CONNECTICUT.

AUTOMATIC STOP FOR DOUBLE-PILE-FABRIC LOOMS.

Application filed March 25, 1926. Serial No. 97,426.

Fig. 1 is a schematic view, mainly in front elevation, of my improved automatic stop for double-pile-fabric looms, the parts being shown in the positions due them under ordinary operating conditions.

Fig. 2 is an enlarged broken sectional view on the line 2—2 of Fig. 1.

Fig. 3 is a view corresponding to Fig. 2 but showing the parts in positions due them 10 when the pile-cutting knife-cord becomes slack for any reason.

Fig. 4 is a broken plan view of the shelf or ledge with the control-lever in section.

This invention relates to an automatic stop 15 for double-pile-fabric looms which are characterized by having a pile-cutting knife for cutting the double-pile fabric into two single-pile fabrics.

The object of this invention is to provide 20 a simple and reliable stop mechanism for such looms which will function to automatically stop the loom and thus prevent damage to the fabric being woven, should the propelling cord of the pile-cutting knife be 25 broken or displaced for any reason.

With this object in view, my invention consists in an automatic stop for double-pile-fabric looms having certain details of construction and combinations of parts as 30 will be hereinafter described and particularly recited in the claims.

In carrying out my invention as herein shown a loom-control box 5 contains appropriate mechanism such as a clutch or electric switch for stopping and starting the 35 loom. This mechanism, whatever its character, is operated by a control-lever 6 extending upward through a clearance-slot 7 in a shelf or ledge 8 forming a part of the loom-frame. The slot 7 is formed with a laterally-offsetting notch providing a shoulder 9 for holding the control-lever 6 in its "on" 40 position against the tension of a spring 10 which tends to move it into its "off" position 45 which is indicated by broken lines in Fig. 1.

Below the shelf 8 and pivoted at 11 to a bracket 12 secured to its underface is a counterbalanced bar 13 carrying an idler-pulley 14 on an extension 15 at its outer end and 50 counterweights 16 at its opposite or inner end. The bar 13 is engaged by a guide-bracket 17 depending from the underface of the shelf 8 and mounts a casing 18 carrying a trip-plunger 19 normally held in its outwardly-extended position by a helical spring 20 encircling its reduced shank portion 21.

A pile-cutting knife 22 is reciprocated as is required to cut a double-pile fabric 23 into two separate single-pile fabrics 24 and 25, such as velvet, plush or similar material (Figs. 2 and 3) by means of a cord or cable 26 passing over the idler-pulley 14 of the bar 13 as well as suitably located pulleys 27, 28, 29 and 30 and around an oscillating driving drum 31 by means of which the cord 26 and hence the knife 22 is moved first in one direction and then in the other.

Under ordinary operating conditions the cord 26 by downward pull on the pulley 14 will maintain the bar 13 in the position in 70 which it is shown by full lines in Figs. 1 and 2 against the counter-urge of the weight 16 whereby the trip-plunger 19, carried by it, is held below the path of the reciprocating reed-beam 32 having reeds 33 and acting in the ordinary manner to "beat up" the filling thread of the fabric 23 as it is being woven.

Having fully described one embodiment of my invention, I shall now proceed to describe the manner of its operation.

In the event that the knife-cord 26 should break or for any reason become dismounted from its pulleys in such manner as to cause slackness in its tension it will thereby permit the counterweights 16 to assert themselves and swing the bar 13 into the position in which it is shown by broken lines in Fig. 1 and by full lines in Fig. 3. In this position the trip-plunger 19 lies in the path of the reciprocating reed-beam 32 and will 90 be engaged thereby with the effect of moving the control-lever 6 out of engagement with the shoulder 9 of the slot 7, thus releasing it to the action of its spring 10 by which it is swung into its "off" position as shown by broken lines in Fig. 1 and the loom thus automatically brought to a stop before any appreciable damage to the fabric can occur.

I claim:

1. In a double-pile fabric-loom, the combination with the power-control mechanism, pile-cutting knife-cord and reed-beam thereof, of a pivotal bar adapted to oscillate in a plane substantially parallel with the said 105 reed-beam, a knife-cord pulley carried by the said bar, a bodily-movable spring-extended trip-plunger also carried by the said pivotal bar and normally held out of the path of the said reed-beam by the tension of the said knife-cord, means yieldingly tending to move the said trip-plunger bodily into the path of 110

the said reed-beam, means for releasably holding the control-mechanism in its "on" position, and yielding means normally urging the power-control mechanism into its "off" position, whereby the trip-plunger is bodily moved into the path of the said reed-beam for engagement thereby to effect the stoppage of the loom when the knife-cord becomes slack.

- 10 2. In a double-pile fabric-loom, the combination with the reed-beam and the operating-lever of the power control mechanism thereof; of a bar pivoted between its ends and adapted to oscillate in a plane substantially 15 parallel with the said reed-beam; a knife-cord pulley and a bodily-movable spring-extended trip-plunger mounted upon one end of the said bar; a counterweight carried

by the opposite end of the said bar; a pile-cutting knife-cord passing over the said pulley, so as to normally overcome the counter-weight and hold the said trip-plunger out of the path of the said reed-beam; means for normally urging the said operating-lever into its "off" position; and means for releasably holding the said lever in its "on" position, whereby, when the said knife-cord slackens its tension, the said trip-plunger is moved bodily into the path of the reed-beam for engagement thereby to effect the release 30 of the said operating-lever and the stoppage of the loom.

In testimony whereof, I have signed this specification.

CHARLES A. BONDIULIS.
